H. GOLDSMITH

FIELDER'S GLOVE

Filed Nov. 20, 1922

Inventor

HUGO GOLDSMITH

By *Walter D. Murray*
Attorney

UNITED STATES PATENT OFFICE.

HUGO GOLDSMITH, OF CINCINNATI, OHIO, ASSIGNOR TO THE P. GOLDSMITH SONS COMPANY, OF CINCINNATI, OHIO, A CORPORATION OF OHIO.

FIELDER'S GLOVE.

Application filed November 20, 1922. Serial No. 602,150.

To all whom it may concern:

Be it known that HUGO GOLDSMITH, a citizen of the United States of America, and a resident of Cincinnati, in the county of Hamilton and State of Ohio, has invented a new and useful Improvement in a Fielder's Glove, of which the following is a specification.

An object of the invention is to provide 10 a fielder's glove wherein the thumb and index finger may be adjusted relatively to one another to suit the individual needs of various ball players.

Another object of my invention is to provide 15 a glove for the purpose stated wherein the means for adjustably limiting the distance between the thumb and index finger will permit ready adjustment, and wherein is avoided the defect resultant from providing 20 metallic eyes. The metallic eye structures heretofore used are subject to the defect of the eyes tearing from the glove.

These and other objects are attained by 25 the means described herein and disclosed in the accompanying drawings, in which—

Fig. 1 is a view showing a glove embodying my invention.

Fig. 2 is a fragmental view showing an 30 inverted thumb of a glove embodying my invention.

Fig. 3 is a view showing the thumb fragment shown in Fig. 2, in another position.

Gloves such as 4 generally comprise a 35 front 5 and a back 6. The front and the back are sewed upon one another along the fingers of the glove as shown at 7. A strip 8 is sewed between the edges 9 and 10 formed on the front and back of the glove. A 40 number of flexible leather strips or straps 11 have their ends 12 and 13 secured between the front and back of the glove by means of the rows of stitching 14 whereby the back and front of the glove are secured 45 about the edges of the fingers and thumb. The edges of the strips 11 are so secured upon the index finger and thumb of the glove that the portions of the strips intermediate the ends of such straps are developed 50 into loops 15 through which a lacing 16 may be passed. The lacing is preferably crossed between the upper and lower pairs of loops 17 and 18 respectively whereby the strands 19 and 20 of the lac-

ing form a closure for the pocket formed 55 between the index finger and the thumb, intermediate the upper and lower pairs of loops. The upper strand 21 of the lacing determines the upper limit of the pocket formed in the glove between the thumb and 60 the index finger.

By reference to Fig. 1 it will be readily apparent that the several strands of the lacing may slide through the loops to permit adjustment of the distance between the 65 thumb and index finger. The strands are also freely movable through the loops whereby to permit ready change in the relation of parts of the strands when a ball is lodged in the pocket, whereby to draw the thumb 70 and index finger about the ball. This structure eliminates the bunching of the leather in gloves of this kind, between the eyelets that are generally carried between the front and the back of the gloves. There are no eyelets 75 that can tear loose from the leather fingers, consequently there is no danger of injury to a ball player who in ignorance of the loosening of an eyelet, may come into contact with such loose eyelet carried by 80 any of the strands of the lacing. Also there is no likelihood to damage to a ball that would come in contact with eyelets loose upon the strands.

What I claim is:

In a glove of the class described the combination of a thumb and an index finger movable toward and away from one another and each comprising a front and a back, the front and the back of the thumb 90 and the index finger respectively having their edges disposed adjacently one to the other, straps having their ends inserted between the edges of the front and back of the thumb and the index finger and having 95 their intermediate portions extending into the space between the thumb and index finger whereby to provide loops intermediate the ends of the straps, a row of stitching passing through the adjacent edges of the front 100 and the back of the glove and through the ends of the straps, and a lacing threaded through the loops of the straps.

In testimony whereof, I have hereunto 105 subscribed my name this 15th day of November, 1922.

HUGO GOLDSMITH.
